US0D1053193S

(12) **United States Design Patent** (10) **Patent No.:** **US D1,053,193 S**
(45) **Date of Patent:** **** Dec. 3, 2024**

(54) **ADAPTER**

(71) Applicant: **SHENZHEN ZOLON TECHNOLOGY CO., LTD.**, Shenzhen (CN)

(72) Inventors: **Jingzhou Hu**, Shenzhen (CN);
Hongwei Wang, Shenzhen (CN);
Yuzhuo Wang, Shenzhen (CN)

(73) Assignee: **SHENZHEN ZOLON TECHNOLOGY CO., LTD.**, Shenzhen (CN)

(**) Term: **15 Years**

(21) Appl. No.: **29/846,752**

(22) Filed: **Jul. 19, 2022**

(30) **Foreign Application Priority Data**

Apr. 15, 2022 (CN) 202230213945.7

(57) **CLAIM**

The ornamental design for an adapter, as shown and described.

DESCRIPTION

FIG. 1 is a top, front, right side perspective view of an adapter, showing my new design;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines are included to show features that form no part of the claimed design.

1 Claim, 8 Drawing Sheets
